US00D978104S

(12) **United States Design Patent** (10) **Patent No.:** **US D978,104 S**
(45) **Date of Patent:** **** Feb. 14, 2023**

(54) **LOUDSPEAKER**

(71) Applicant: **RCF S.P.A.**, Reggio Emilia (IT)

(72) Inventors: **Giorgio Aldini**, Reggio Emilia (IT);
Gabriele Mattioli, Reggio Emilia (IT)

(73) Assignee: **RCF S.P.A.**, Reggio Emilia (IT)

(**) Term: **15 Years**

(21) Appl. No.: **29/799,838**

(22) Filed: **Jul. 16, 2021**

Related U.S. Application Data

(62) Division of application No. 29/731,469, filed on Apr. 15, 2020, now Pat. No. Des. 938,933.

(57) **CLAIM**

The ornamental design for a loudspeaker, as shown and described.

DESCRIPTION

FIG. 1 is a perspective view of a loudspeaker, showing the new design;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The broken lines in the drawings represent portions of the loudspeaker that form no part of the claimed design.

1 Claim, 4 Drawing Sheets
